UNITED STATES PATENT OFFICE

JOSEPH RICE, OF CHICAGO, ILLINOIS, ASSIGNOR TO ELEVATOR COMPANY OF AMERICA,
OF CHICAGO, ILLINOIS, A CORPORATION OF ILLINOIS

SWINGING-DOOR-CONTROL DEVICE FOR ELEVATORS

Application filed September 15, 1927. Serial No. 219,689.

My invention relates to door controlled mechanism for elevators and has for its object the provision of a door control particularly applicable to doors provided at the different landings of the elevator shaft which are hinged to swing into and out of closing position.

It is a purpose of this invention to provide a door controlled mechanism of this character which will lock the door in closed position so as to prevent unauthorized opening thereof but which will permit the door to be open when the elevator car is at the particular landing where the door is situated.

It is also a purpose of this invention to provide a door locking mechanism which positively locks the door in closed position and which may be released by turning the knob of the ordinary door latch.

Another object of this invention is to provide in combination with the door locking mechanism hereinbefore mentioned means for closing the operating circuit for the elevator car when the door is in closed position and opening the same so as to prevent the operation of the car unless the door is firmly locked in closed position.

Other objects and advantages of the invention will appear as the description proceeds when taken in connection with the accompanying drawings. However, I wish it to be distinctly understood that I do not intend to limit myself to the exact details shown and described but that I intend to avail myself of all such modifications as would occur to one skilled in this art and as fall within the scope of the claims.

In the drawings:

Fig. 1 is a side view taken from the interior of the elevator shaft of the door controlled mechanism;

Fig. 2 is an end view of the door taken at right angles to Fig. 1 along the line 2—2 of Fig. 1; and

Fig. 3 is a diagrammatic sketch showing the position of the door controlled contacts in the operating circuit for the elevator.

Referring now in detail to the drawings, the numeral 5 indicates the casing surrounding the door opening provided at a landing in

the elevator shaft. A door 6 is hinged to the casing 5 as shown at 7 in Fig. 2 so as to swing outwardly when it is desired to enter a car at the landing. This door is provided with the regular door latch mechanism indicated by 8, operating shaft 9 and door knob 10. The connection between the shaft 9 and the latch 8 may be of any standard construction that is used for door latches.

It will be noted that the shaft 9 does not extend all the way through the door, but is provided with an enlarged portion 11 adjacent the outer face of the door, which portion 11 is provided with a recess to receive the key 12 in case it is desired to unlock the door from the outside. The key 12, obviously, is only to be used in case of emergency when for some purpose the door must be opened from the exterior of the elevator shaft.

The shaft 9 is provided with a crank arm 13 to which is connected the upwardly extending rod 14 guided on the door by means of the bracket 15 and carrying at its upper end a roller 16 which is preferably made of insulating material. Adjacent the upper end of the rod 14 there is provided a plate 17 secured to the door and having the inwardly projecting locking member 18 thereon. This locking member as shown clearly in Fig. 2 is provided with a pair of teeth 19 and 20 adapted to engage corresponding teeth 21 and 22 on the lever arm 23 which is pivoted to the housing 24 mounted on the door casing 5. The shaft 25 which serves as a pivot for the lever arm 23 also has the arm 26 preferably consisting of a fairly heavy metal bar secured thereto. This arm extends toward the door and is adapted to engage with the roller 16 on the upper end of the rod 14. Thus when the rod 14 is in the position shown in Figs. 1 and 2, the arm 26 and the roller 16 permit the teeth on the lever arm 23 and the projection 18 to engage and thus lock the door in closed position. This is also preferably the position in which the latch 8 is extended to latch the door to the casing 5.

Now when it is desired to release the door, the door knob 10 is rotated in the direction indicated by the arrow in Fig. 1 which raises the rod 14 and thereby the arm 26, and

through the shaft 25, the arm 23 so as to disengage the interlocking teeth on arm 23 and projection 18 and permit opening of the door. In order to prevent leaving the doors open due to carelessness on the part of the operator of the elevator, I provide within the casting 24 a pair of spring pressed contacts 28 and 29 which are connected by means of the leads 30 and 31 and suitable wiring to the motor 32 by which the elevator car is driven. As is commonly the case, the elevator car itself is equipped with a control lever 33 for operating the same, which control lever 33 also serves to close the circuit to the motor 32.

15 Cooperating with the spring contacts 28 and 29 is the projecting lug 35 on the door 6 which lug has a round head portion 36 extending between the spring contacts 28 and 29 to complete the circuit when the door is in closed position. The projections 18 and 35 are preferably made of such length that when the door is being brought to closed position, the teeth 19 and 22 will interlock so as to prevent opening of the door before the knob 36 completes contact between the spring contact members 28 and 29 but when the teeth are engaged in the position shown in Fig. 2, the knob 36 is forced between the spring contacts 28 and 29 so as to make a good connection. This makes it necessary for the elevator operator in order to start his car to completely close and lock the door at each landing.

25 35 As a further means of insuring the permanent locking of the door, the arm 23 is pressed downwardly by means of the spring 37 mounted in the housing 24.

40 From the above description it is thought that the construction and operation of this device will be clear to those skilled in the art and having thus described my invention, what I claim and desire to secure by Letters Patent of the United States is:

45 1. Door control mechanism for elevator installations wherein the doors at the different floor levels are mounted to swing into and out of closing position, comprising interengaging locking members carried by said door and the door frame adapted to lock the door in closed position, contacts mounted on the frame and adapted when closed to complete a circuit for operating the elevator, means rigidly mounted on the door for connecting said contacts when the door is in closed position and means for releasing said locking members and opening the door from within the elevator shaft comprising a handle on said door and mechanism operable by movement of said handle to move one of said locking members out of engagement with the other to permit opening of said door.

50 2. Door control mechanism for elevator installations wherein the doors at the different floor levels are mounted to swing into and

out of closing position, comprising interengaging locking members carried by said door and the door frame, the member on the door frame being movable to disengage said members, a door handle on said door accessible from an elevator car at said door, a crank arm connected to said handle and means connected with said crank arm for moving said movable member to permit opening of said door when said handle is turned.

55 3. Door control mechanism for elevator installations wherein the doors at the different floor levels are mounted to swing into and out of closing position, comprising interengaging locking members carried by said door, and the door frame, one of said members being movable to disengage said members, a door handle on said door accessible from an elevator car at said door, an actuating arm connected to said movable member, means connected to said handle and engaging said actuating arm whereby movement of said handle causes movement of said movable member and resilient means cooperating with said movable member to urge the same into door locking position.

60 4. Door control mechanism for elevator installations wherein the doors at the different floor levels are mounted to swing into and out of closing position, comprising interengaging locking members carried by said door, and the door frame, a pair of contacts on said door frame adapted when connected to complete a circuit permitting the operation of an elevator car, a bridging member on said door connecting said contacts when said door is in closed position, and a door knob having means connected therewith to disengage said locking members and permit opening of said door when said knob is turned.

65 5. Door control mechanism for elevator installations wherein the doors at the different floor levels are mounted to swing into and out of closing position, comprising interengaging locking members carried by said door, and the door frame, a pair of contacts on said door frame adapted when connected to complete a circuit permitting the operation of an elevator car, a bridging member on said door connecting said contacts when said door is in closed position, and a door knob having means connected therewith to disengage said locking members and permit opening of said door when said knob is turned, said means including a rod movable vertically on said door and having a roller at the top thereof and an actuating arm on one of said locking members with which said roller engages when the door is closed.

70 6. Door control mechanism for elevator installations wherein the doors at the different floor levels are mounted to swing into and out of closing position, comprising interengaging locking members carried by said door, and the door frame, a pair of contacts on said

door frame adapted when connected to complete a circuit permitting the operation of an elevator car, a bridging member on said door connecting said contacts when said door is in closed position, and a door knob having means connected therewith to disengage said locking members and permit opening of said door when said knob is turned, said locking members having portions thereon for locking said door against opening prior to engagement of said bridging member with said contacts, when the door is being moved from open to closed position.

7. Door control mechanism for elevators comprising a latch on said door, means on the door frame with which said latch is adapted to engage to hold said door in closed position, a handle on said door accessible from the interior of the elevator shaft for operating said latch, interengaging locking members on said door and frame for locking said door in closed position and connecting means between said handle and locking members whereby movement of said handle to release said latch disengages said locking members, said connecting means including a crank arm connected to said handle and a rod movable vertically on said door to lift one of said locking members.

30 In witness whereof, I hereunto subscribe my name this 1st day of September, A. D., 1927.

JOSEPH RICE.
